DESIGN FOR A BUTTON CLOSING FASTENER

Harry Cohen, New York, N. Y.

Application November 17, 1941, Serial No. 104,178

Term of patent 3½ years

To all whom it may concern:

Be it known that I, Harry Cohen, a citizen of the United States of America, residing in New York city, county of New York, and State of New York, have invented a new, original, and ornamental Design for a Button Closing Fastener, of which the following is a specification, reference being had to the accompanying drawing, forming part thereof.

Fig. 1 is a plan view of a button closing fastener showing my new design.

Fig. 2 is an edge view thereof.

Fig. 3 is a plan view with the button closing fastener in open position.

I claim:

The ornamental design for a button closing fastener, substantially as shown.

HARRY COHEN.
